UNITED STATES PATENT OFFICE.

JOHN G. LEWIS, OF ST. LOUIS, MISSOURI.

WORK-HANDLING MECHANISM FOR BLINDSTITCH SEWING-MACHINES.

1,254,818.

Specification of Letters Patent. Patented Jan. 29, 1918.

Original application filed December 24, 1910, Serial No. 599,071. Patented February 22, 1916, No. 1,172,812.
Divided and this application filed December 6, 1913. Serial No. 805,160.

To all whom it may concern:

Be it known that I, JOHN G. LEWIS, a citizen of the United States, residing at St. Louis, in the city of St. Louis and State of Missouri, have invented certain new and useful Improvements in Work-Handling Mechanism for Blindstitch Sewing-Machines, of which the following is a specification.

My invention relates to improvements in 10 sewing machines, and in some of its features more particularly to blind stitch sewing machines, especially of the type illustrated in my copending application, Serial No. 599,071 filed December 24, 1910, which matured into 15 Patent No. 1,172,812, dated February 22, 1916, of which application this is a division.

Among the general objects of my invention I seek to provide a machine readily adapted, in the character of its work-handling mechanism, to widely different sorts of work; capable of high speed and fast operation; suitable for handling materials of widely varying thickness and abruptly changing numbers of plies; and generally 25 of simple and efficient construction and organization.

The many novel features of my invention productive of improved and novel mechanical organization, and resulting in the performance of novel functions may best be ascertained from the appended claims in conjunction with the following specification and accompanying drawings.

In the drawings

35 Figure 1 is a front elevation of a "flat-bed" machine; *i. e.*, a machine for handling flat work, and accordingly having a wide work-support;

Fig. 2 is an end elevation with parts in 40 section showing the work handling mechanism and associated presser foot;

Fig. 3 is a sectional view on line 3—3 of Fig. 7 showing said mechanism from the opposite side;

45 Fig. 4 is a vertical section on line 4—4 of Fig. 2;

Fig. 5 is a plan view of the parts shown in Fig. 2;

50 Fig. 6 is a sectional detail on line 6—6 of Fig. 7;

Fig. 7 is a vertical section through the lower arm of the machine;

Fig. 8 is a detail of the spring support; Fig. 9 is a sectional detail on line 9—9 of Fig. 7;

55 Fig. 10 is an enlarged vertical section through the rear post of the machine;

Fig. 11 is a cross section through said post;

Fig. 12 is an enlarged detail of the feed- 60 length-adjusting eccentric;

Fig. 13 is a section on line 13—13 of Fig. 12;

Fig. 14 is a sectional detail of a plunger and clamp; 65

Fig. 15 is a sectional detail showing such plunger and a co-operating presser foot.

The machine organization in general, as herein shown, preferably comprises a frame 20 having an upper arm 21, carrying the 70 head 22 for the stitching mechanism. In said head are arranged the moving parts of the stitch-forming mechanism, working above the presser foot 23, which may be substantially stationary. The upper arm 21 projects from the standard or post 25 supported by a base casting 26 constituting a lower arm 75 of the machine, and affording support to the working parts of the work-handling mechanism generally indicated at 27, (Fig. 1). 80

In the particular construction shown the base 26 is adapted to fit an opening cut therefor in a work table 28 and above the frame there is provided a flat work support 29 pivoted as at 30 in ears provided on the 85 frame 26, and bearing near its free end on an adjustable stop 30'. The work support 29 is provided with a suitable opening 31 through which the feed and plunger mechanism may work, such opening preferably 90 flanked by slide plates 32 removable to give ready access to the subjacent parts.

Stitch forming mechanism, such as that generally illustrated in Fig. 1, is fully described in my copending application, of 95 which this is a division, and for present purposes it suffices to say said stitch forming mechanism 22 comprises a reciprocating, curved, side pointed needle 22^a working above the presser foot and co-operating with a rotary hook 22^b and suitable thread controlling parts, for the formation of blind lock stitches, the needle entering and emerging from the same side of the work which is 100

presented to the action of the needle through an opening 23^a in the presser foot 23.

The work handling devices comprise in general, a plunger or bender reciprocable to present the stitch-receiving portion of the goods through the presser foot opening 23^a; clamping means to coöperate with the presser foot to clamp the goods thereagainst at the time the plunger elevates the node of goods through the presser foot opening; and a 4-way feed structure. The active parts of these instrumentalities receive motion from these shafts 41, 42, and 43 extending longitudinally through the lower arm of the machine and at their outer ends finding bearing in a head block 40 which is preferably in the form of a major segment of a cylinder, attached to the base by screws 40'. The arrangement shown is advantageous in that it brings all of the longitudinal shafts of the base into an area of small compass so that, if desired, said shafts and mechanisms may be readily mounted on a base cylinder of relatively small size in lieu of the flat-bed, the block 40 conforming to the end of such a cylinder. In this way the machine may be set up for work on sleeves, trousers' bottoms and the like, with only a change of the base casting and work support.

The plunger or bender generally indicated at 45 is a vertically reciprocating member operated by the rock-shaft 41. It is provided with an appropriately shaped nose or tip to coöperate with the back of the goods in elevating a node of goods through the presser foot opening 23^a. In the particular construction shown, 46 indicates a barrel of the plunger mounted to slide vertically in a guide opening in head block 40, the bottom of said barrel being reduced to form a throat 47 secured in an offset lug 48 projecting from a slide plate 49 which works in a slide way 50 in the inner face of the head block 40, said slide way opening to a recess 51 across the bottom of the block to accommodate the movement of the lug 48. To impart vertical movement to the slide 49 the plunger-operating rock-shaft 41 has a crank 53 having a pivotal connection with link 54, the opposite extremity of which is pivotally connected to the slide 49. In order that the limit of vertical movement of the slide 49 may be varied and the limit of movement of the plunger correspondingly changed, the connection between the slide 49 and the upper extremity of link 54 is made adjustable. To this end the upper extremity of link 54 is formed into a clamp 55 engaging a rotarily adjustable sleeve 56 eccentrically apertured and surrounding a pin 57 projecting from the slide 49. Obviously by rotating the eccentric 56 by means of its knurled head 58,

and clamping it in desired position, effective variation in the limits of throw of the plunger may be attained at will.

The tip or nose of the plunger is preferably yielding relative to the body or positively-moved part thereof, to constitute a yielding back guide. To this end the head 60 is mounted on a stem 61 extending into the central bore of the barrel 46 and reduced at its lower end, as at 62 to pass through the throat 47 and receive the exterior stop nuts 63. The reduced portion 62 of the stem is surrounded by a coiled spring 64 yieldingly maintaining the stem at its upper limit of movement relative to the barrel. Rotation of the stem relative to the barrel is prevented by slot and key engagement therebetween, as shown by key 65 and slots 66. The yieldability of the plunger thus provided is particularly advantageous in relieving the machine from strain under extraordinary increases in the thickness of work.

Preferably the power connections of the plunger mechanism, or its rock shaft 41, are such that in the rocking movements of the shaft, occurring with each revolution of the main shaft, (through connections hereafter described), one crank arm in the train swings to, or, moves desirably, past dead center slightly so that the operation of the plunger is to rise from lowest to highest position and then to dwell, or to dip or recede slightly, before commencing its return movement to lowest position; in the latter instance securing what I will term a secondary retraction of the plunger tip, of considerable time duration, but slight linear extent, occurring while the plunger is adjacent its upper limit of movement, in its position of functional coöperation with the needle.

In operative association with the plunger I provide a clamping mechanism for coöperation with the presser foot to clamp and steady the goods contiguous to the presser foot opening so that the plunger may draw the clamped goods taut and so hold them before and at the time of needle penetration. It is preferable that these two coöperating parts—plunger and clamp—shall be inter-related so that one is carried by the other yieldably through the inter-position of a spring between the parts, in order that wear in the operating parts may not change their special relationship or affect their co-operative functioning, and to insure their proper coaction with goods of widely-varying thickness.

In the particular construction shown I prefer that the plunger or bender be the positively driven part, sliding in the frame to define the line of movement of the two coöperating mechanisms—plunger and

clamp—and therefore I mount the clamp member yieldingly upon the plunger for bodily movement therewith. Particularly, in the operation of the machine, the goods should be retained and clamped on that side of the plunger adjacent to the point of entrance of the needle in order that the goods may not give to the thrust of the needle and may not tend to follow the needle in its reciprocating movement. The precise configuration of the clamping means will, of course, be varied to correspond with such variations as may be made in the precise form of plunger head, but in the specific construction shown, the clamp 70 is a cup shaped member surrounding, or substantially surrounding, the head of the plunger and yieldably mounted upon the plunger for reciprocation therewith. 71 indicates the rim of the clamp, the upper edge of which constitutes the clamping surface surrounding and spaced apart somewhat from the plunger head to operate against the under side of the presser foot. 72 indicates the annular base of the clamp member surrounding the stem 61 of the plunger below its head. A spring 73 interposed between the plunger barrel 46 and the clamp base, normally maintains the clamp with its stop pins 74 abutting against a stop pin 75 of the plunger and guided in the side slots 66 of the plunger, these parts having sufficient looseness of fit so that the clamp is capable of yielding movement to tilt universally to some extent relative to the plunger head, the clamp obviously being slidable longitudinally upon the plunger stem. If desired pins 74 may be omitted and the clamp left free to rotate.

40 The plunger head may be suitably shaped according to the character of the work to be done, a rounded plunger being one commonly employed in certain classes of work, and when such construction is used the presser foot opening 23^a is usually appropriately shaped to give a clear orifice slightly greater than the size of the plunger tip. In some classes of work, however, as in felling edges, the machine may be given a capacity for handling without readjustment, materials of widely varying thickness, limiting the stitch to a given depth, by appropriate relation of the presser foot and plunger. Under such circumstances the plunger is preferably constructed with a head having lateral extensions 60^a as shown in Fig. 15, and the path of movement of said extensions may be partially overlaid by stops or front-guide projections 23^b flanking the presser foot opening. With this arrangement, the front face, or "stitching side" of the goods, cannot be raised by the plunger above a predetermined plane, the plunger tip yielding against spring 64 after it has brought the face of the work to such plane. Therefore the needle, reciprocating in a constant path accurately predetermined, cannot strike deeper into the goods than the setting of these parts of the machine will permit, so insuring that the stitching shall be confined to the desired plies or depth of the goods. When the goods imposed on the plunger are not thick enough to reach the front guide or stop, the natural limit of movement of the plunger, acting under such circumstances as a "back" guide, prevent the goods from being raised so far as to cause the stitching to show through on the fair side of the goods, and where no front guide or stop is used, the plunger raises the fair side of the goods to substantially uniform position under widely varying thicknesses of work. It will be noted hereinafter that after the plunger rises to its highest point, it may dip or bob slightly, after the needle has started to penetrate the goods, so relieving from any grinding or abrading action that portion of the goods lying between the moving needle and the plunger, and serving other useful functions incident to successful and high speed work.

45 The feeding of the goods is accomplished by a feed dog 80, operating against the under surface of the presser foot and driven laterally of the shafts, or fore-and-aft as to its direction of feed, from the "lateral" feed shaft 42, and vertically from the "vertical" feed shaft 43. The feed dog 80 is thus driven entirely by axially fixed, solid shafts, dispensing with universal joints or other means for attaining flexibility, but the mounting and connections of the dog are such that it has a desirable and sufficient capacity for adaptive movements. Thus the dog is preferably swiveled on a horizontal axis and is capable of rocking motion to compensate for variations in thickness of material interposed between the presser foot and different fore-and-aft areas of the dog, thereby to enable different points of the toothed surface of the dog appropriately to coact with the work. Also the dog is preferably so mounted upon a carrier, spring pressed to normal position, that at any plane of its cyclic operation and regardless of whether or not the drive shafts are in motion, the dog may be depressed to permit the insertion, removal or shifting of the work. To the latter end, I provide in the connection with the feed dog to the "lateral" feed shaft 42 a generally horizontal pivotal connection and in the connection of said dog to the "vertical" feed shaft 43 I provide a generally horizontal connecting element associated with the vertically slidable spring pressed carrier so that the feed dog may make vertical excursions with the vertically moving carrier, without substantially dis-

turbing its relation to the drive shafts or to those driving connections which impart movement from the drive shafts to the feed dog. In the particular construction shown, 5 the dog is provided with three feed points 81, two of which preferably flank the plunger and clamp mechanisms, while the third is in front of the plunger with reference to the direction of feed. To the forward extremity of the feed dog is connected, preferably pivotally, a wide link 82 arranged at a relatively small angle to the horizontal and at its remote extremity said link is pivoted to a crank 83 mounted on the shaft 10 42 to be moved fore-and-aft by the rocking of said shaft. At a suitable point, preferably near its fore-and-aft center, the feed dog has pivotal connection to the extremity of a generally-vertical link 84, and because 15 of the pivotal connection of the feed dog to both of the links 82 and 84 its normal, substantially horizontal, presentation to the presser foot is maintained by a spring 85, connected between a pin 86, on the link 84, 20 and a pendant tail 80' of the feed dog. The lower extremity of the link 84 is pivoted to a horizontal arm of a bell crank lever 88, the vertical arm of which, upwardly extending, has connection by a substantially-horizontal link 89, with the crank lever 90 working fore-and-aft on the extremity of the "vertical" feed shaft 43. Obviously the appropriately timed rocking of the two shafts 25 42 and 43 will impart 4-way feed motion 30 to the feed dog.

The pivot 88', on which the bell-crank lever 88 is mounted, is a part of a carrier or carriage 91, said carrier comprising a suitable guide post 92 lying in a suitable 35 opening in the head block 40 and a head 93 to which said part is secured by a screw 94 extending through the pivot portion 88'. The carriage head 93 works in a recess 95 in the head block 40, and upon the head 93 I 40 preferably mount a bumper spring 96 to ease the action of the carriage under high speed. The carriage is normally spring pressed upwardly as by a strong leaf spring 98, the tip of which engages in a recess 99 45 in the carriage head 93. The base of the spring 98 passes over a fulcrum lug 100 on the frame and near its extremity it is engaged by a block 101 adjustable to vary the tension of the spring, as by means of 50 an adjusting screw 102, extending through the block and spring and through a fixed lug 103 of the frame.

The spring 98 holds the carriage 91 normally in raised position so that the 4-way 55 movement of the feed may occur in proper vertical relation to the goods to be fed, and to the under side of the presser foot, but it will be observed that the carriage may be depressed against the tension of its leaf

spring, either incidentally to the functional 65 operations of the feed or for the purpose of dropping the feed to permit the goods to be inserted, removed, or shifted. Obviously, when the carriage is depressed, carrying with it the pivot member 88' for the bell 70 crank lever 88 of the feed system, the lowering of the bell crank lever draws down the link 84 and with it the feed point, the generally horizontal link 89 and the generally horizontal link 82 both swinging downward to accommodate the displacement of the feed point and bell crank lever. Neither of these links need be in precisely horizontal position to accommodate this movement, but they should afford a sufficient approximation to a parallel link motion so that the lateral displacement of their moving ends may be relatively small, compared to the vertical displacement. The arrangement shown is such that the depression of 80 the carriage and the feed dog may take place regardless of the position of the cranks 85 and 90 in the cyclic operation of the feed, and when the carriage is depressed the feed dog will continue to effect its 4-way move- 90 ments.

Any appropriate means may be provided for depressing the carriage 91 at will, the construction herein shown providing a rocking frame 104 arranged to act on the spring 98, and a "knee lift" for actuating said frame. Specifically 105 and 105' indicate end arms of the frame, both loosely pivoted on the plunger shaft 41, and connected by a frame bar 106, one of said arms, as 105, having an extension 106' to act on the spring 98 near its active end and the other arm having a lever extension 107 for operation by the knee lift mechanism 108 upon the table 28. A spring 109 normally holds the rock- 105 ing frame retracted.

The three rock shafts 41, 42, and 43 are driven and timed by three eccentrics 111, 112 and 113 respectively, mounted on the main shaft 10, above the post 25 through 110 which the arms 121, 122 and 123, respectively, of the several eccentric straps, extend for connection with the cranks appurtenant to the rock shafts 41, 42 and 43. Eccentrics 111 and 113 for the plunger shaft and the 115 "vertical" feed shaft may be set or fixed eccentrics of any usual character. The eccentric 112 for operating the "horizontal" feed shaft 42 is preferably adjustable as to its eccentricity in order that the length of 120 fore-and-aft throw the feed dog may be varied to change the spacing between stitches. As a simple means to this adjustment, cam 112 is made in the form of an annular ring with a large center opening 125 carried by a plate 114 which has an offset end lug 115 guided in an edge recess 116 in a disk 117 fast on the shaft, said plate

being additionally guided by a slot and pin connection with the disk, as shown at 118. An adjusting screw 119 taking through the lug 115 into the block 117, and springs 120

5 acting between the bottom of the recess 116 and the lug 115 serve to effect and to hold the desired adjustment of the eccentric, changing the degree of its eccentricity but not its time with reference to the main shaft.

10 The arm 121 moved by the eccentric 111 is connected to the mid portion of a lever 125 which is pivoted near its one end to a depending lug 126 of the end wall of the frame and which is connected at its other

15 end by link 127 with the crank arm 128 on the shaft 41, said shaft at its rear end being journaled in said lug 126. The other two shafts 42 and 43 stop short of the end wall lug 126 so as not to interfere with the movement just described, said shafts being supported adjacent their rear end by a lug 129, depending from the frame in substantial alignment with the inner side of the post 25. The strap arm 122 of the adjustable eccentric

20 for the feed is connected direct to the wrist pin of crank 130 carried by "horizontal" feed shaft 42 and strap arm 123 for the remaining eccentric 113, has pivotal connection with the wrist pin of crank 131

25 mounted on "vertical" feed shaft 43.

It will be noted with respect to the linkage connection from eccentric 111 to rock shaft 41 that the throw imparted to the shaft 41 will be of considerable angular extent, and

30 the relation between the two cranks 128 and 53 carried by said shaft 41 is preferably such, as heretofore described, that the crank 53 is thrown over dead center as crank 128 approaches its upper limit of throw.

35 Among the important features of the construction described, is the capability of the feed mechanism to be lowered at will, regardless of the position of either of the inflexible shafts 41 and 42 in their cyclic operation. This arrangement permits the operator to substitute manual control of the feeding of the goods for the automatic feed at any time when the exigencies of the work may so require. For instance, sharp

40 turns in the goods, to change the direction of the lines of stitching, may be made, and—especially when the machine is being operated as in tacking, padding collars or the like,—the operator may sew forward and backward at will, allowing the forward feed to be effected by the automatic feed mechanism and (after depressing the feed) drawing the goods backward by hand.

45 During such a manual feeding operation the clamp operates to clamp the goods during every penetration of the needle so obviating the possibility of damaging the needle and also insuring proper tensioning of the goods on each such stitch. Obviously

the goods may be shifted or fed laterally 65 while the feed dog is held out of commission and thus blind stitch tacking may be done rapidly and facilely.

The action of the clamp insures proper tensioning of the goods against the thrust 70 of the bender or plunger at all times; its yieldability in all directions gives it the quality of accommodating itself to varying thicknesses of work, be they in lateral or fore-and-aft direction with respect to 75 the line of feed; and the inter-relation of the clamp and the plunger so that one is carried by the other and the carried element is spring supported with respect to the other, gives them an automatic compensation to 80 take up the effect of wear, in their operating mechanism, and a certainty of proper coaction with the goods, which in practice is found to be highly advantageous.

While I have herein described in some 85 detail a particular embodiment of my invention, which I have commercially used and found to be highly desirable in many of its structural details, as well as in the general combination of elements, it will be 90 understood by those skilled in the art that many changes in the specific embodiment might be made without departure from the spirit of my invention and within the scope 95 of the appended claims.

What I claim is:

1. In a blind stitch sewing machine, the combination of a presser foot having an opening, a plunger working into said opening to present work therethrough, a clamp 100 co-operating with said presser foot contiguous to the plunger, said clamp and plunger being bodily movable together and one yieldingly carried by the other, and means to reciprocate that one which carries the other. 105

2. In a blind stitch sewing machine, the combination of a presser foot having an opening, a plunger working into said opening, a clamp contiguous to said plunger, co-operating with the presser foot, said clamp 110 and plunger being bodily movable together and one yieldably carried by the other, for relative movement between them, and means for positively raising the plunger.

3. In a blind stitch sewing machine, the 115 combination of a presser foot having an opening, a plunger working into said opening, means to reciprocate said plunger, and a clamp mounted on said plunger for reciprocation therewith, and yieldable relative to 120 the plunger.

4. In a blind stitch sewing machine, the combination of a presser foot having an opening, a plunger working into said opening, a clamp surrounding said plunger, a 125 spring interposed between said clamp and plunger, normally maintaining said parts with their upper ends at predetermined rel-

ative levels, and means for reciprocating said plunger with respect to said clamp to raise its active end above the clamp against the tension of said spring.

5. In a blind stitch sewing machine, the combination of a presser foot having an opening, a plunger working into said opening, means for reciprocating said plunger from and toward said opening, and a clamp 10 yieldingly mounted on said plunger for reciprocation therewith to act against the presser foot.

6. In a blind stitch sewing machine, the combination of a presser foot having a cloth opening, a plunger arranged to work into said opening, means for reciprocating said plunger toward and from said opening, a clamp loosely surrounding the plunger for limited movement longitudinally thereof, 20 and a spring yieldingly positioning the clamp at one extreme of its movement relative to the plunger.

7. In a blind stitch sewing machine, the combination of a stationary presser foot 25 having a cloth opening, a plunger to work into said opening, means for reciprocating the plunger toward and from said opening, and a clamp yieldingly mounted on said plunger for reciprocation therewith to act 30 intermittently against the presser foot.

8. In a blind stitch sewing machine, the combination of a presser foot having a cloth opening, a plunger to work into said opening, means for reciprocating said plunger 35 toward and from said opening, and a clamp carried by said plunger arranged to tilt universally with reference to the plunger.

9. In a blind stitch sewing machine, the combination of a presser foot having a cloth 40 opening, a plunger to work into said opening, means for reciprocating said plunger toward and from said opening, and a clamp carried by said plunger arranged to tilt with reference to the plunger.

45. 10. In a blind stitch sewing machine, the combination of a presser foot having a cloth opening, a plunger to work into said cloth opening, means for reciprocating said plunger toward and from said cloth opening, 50 and a clamp mounted on said plunger to reciprocate therewith to act intermittently against the presser foot, said clamp being yieldingly mounted upon the plunger to tilt universally and slide longitudinally relative 55 to said plunger.

11. In a blind stitch sewing machine, the combination of a presser foot having a cloth opening, a plunger to work into said cloth opening, means for reciprocating said plunger toward and from the cloth opening, and a cup-shaped clamp member yieldingly mounted upon the plunger.

12. In a blind stitch sewing machine, the combination of a presser foot having a cloth

opening, a plunger to work into said cloth opening having a yielding tip, and means to reciprocate said plunger.

13. In a blind stitch sewing machine, the combination of a presser foot having a cloth opening, a plunger to work into said opening, 70 compressible between its ends, and means to reciprocate said plunger.

14. In a blind stitch sewing machine, the combination of a presser foot having a cloth opening, a compressible plunger to work 75 into said opening, and means to reciprocate said plunger positively between predetermined limits of travel.

15. In a blind stitch sewing machine, a presser foot having a cloth opening, a 80 plunger comprising a barrel, a head having a stem extending into said barrel, and a spring interposed between said head and barrel, and means to reciprocate said plunger to cause it to work into the cloth 85 opening.

16. In a blind stitch sewing machine, the combination of a presser foot having a cloth opening, a two-piece plunger comprising a body portion and a removable tip, means surrounding said body portion to guide it 90 axially, and means to reciprocate said plunger.

17. In a blind stitch sewing machine, the combination of a presser foot having an 95 opening, a plunger, and means for reciprocating said plunger toward and from said opening, arranged to impart to the plunger a dip while the plunger is at generally the extreme of its movement toward the presser 100 foot.

18. In a blind stitch sewing machine, the combination of a presser foot having a cloth opening, a plunger, a rock shaft on said plunger and connections between said shaft 105 and the plunger, to reciprocate the plunger toward and from the presser foot opening, and to effect a secondary retraction of the plunger while the latter is at approximately the extreme of its movement toward the 110 presser foot.

19. In a blind stitch sewing machine, the combination of a presser foot having a cloth opening, a plunger to work therein, a rock shaft for said plunger, and operative connection between said plunger and shaft comprising a crank arranged to be thrown past dead center with respect to the plunger, in the course of the oscillation of the shaft, thereby to cause a secondary retraction of 120 the plunger of small extent while the plunger is adjacent the extreme of its range of movement toward the presser foot.

20. In a blind stitch sewing machine, the combination of a presser foot having an 125 opening, a front guide part carried by said presser foot contiguous to said opening, a yielding plunger to coöperate with said

- opening and front guide part, and means to reciprocate said plunger between predetermined limits of travel.
21. In a blind stitch sewing machine, the combination of a presser foot having a cloth opening, feed devices on one side of the presser foot comprising a feed dog, means for operating said feed dog, and means for throwing said feed dog into or out of position while the machine is in operation, a plunger on the same side of the presser foot, means to reciprocate said plunger toward and from the cloth opening in the presser foot, and a clamp carried by the plunger.
22. In a blind stitch sewing machine, the combination of a presser foot having a cloth opening, feed devices on one side of the presser foot comprising a feed dog, means for operating said feed dog, and means for throwing said feed dog into or out of position while the machine is in operation, a plunger on the same side of the presser foot, means to reciprocate said plunger toward and from the cloth opening in the presser foot, and a clamp carried by the plunger.
23. In a blind stitch sewing machine, the combination of a presser foot having a cloth opening, feed devices on one side of the presser foot comprising a feed dog, means for operating said feed dog, and means for throwing said feed dog into or out of position while the machine is in operation, a plunger on the same side of the presser foot, means to reciprocate said plunger toward and from the cloth opening in the presser foot, a clamp arranged to act upon a small area of the goods contiguous to the plunger and yieldable relative to the presser foot.
24. In a blind stitch sewing machine, the combination of a presser foot having a cloth opening, stitch-forming mechanism above the presser foot, feed mechanism below the presser foot comprising a feed dog, means for actuating said feed dog for cyclic movements, means for throwing said feed dog into or out of operative relations to the presser foot during the operation of the machine, a plunger reciprocable from and toward the presser-foot opening, a clamp arranged to coact with a small area of the goods contiguous to the plunger to clamp the same against the presser foot, and means to reciprocate the plunger and the clamp.
25. In a blind stitch sewing machine, the combination of a presser foot having a cloth opening, a plunger to work therein, a clamp yieldingly carried by the plunger, and means to reciprocate said plunger comprising a rock shaft, a crank thereon, and an adjustable connection between the crank and plunger.
26. In a blind stitch sewing machine, the combination of a presser foot having a cloth opening, a plunger to work therein, a clamp yieldingly carried by the plunger and arranged to tilt thereon, and means to reciprocate said plunger comprising a rock shaft, a crank thereon, and an adjustable connection between the crank and plunger.
27. In a blind stitch sewing machine, the combination of a frame providing a base, and an overhanging arm, stitch-forming mechanism, and a stationary presser foot carried by said arm, a base providing fixed bearings at opposite ends, three shafts in the base having fixed bearings therein, and located in a sectional area of small compass, a plunger operatively connected to one of said shafts for reciprocation to coöperate with the presser foot, a feed dog operatively connected to the other two shafts to receive from one thereof a horizontal component of movement and from the other its vertical component of movement, and means to depress said feed dog to an inoperative plane without disturbing its shaft.
28. In a blind stitch sewing machine, the combination of a presser foot having a work opening, stitch forming means working on one side of the presser foot to enter and emerge from the same face of work presented through said presser foot opening, a feed part opposing said presser foot and a clamp arranged to coact with said presser foot through the work and to tilt to accommodate inequalities of work-thickness, said clamp and feed part being on the same side of the presser foot.
29. In a blind stitch sewing machine, the combination of a presser foot, a feed part opposing the presser foot, and a clamp co-acting with the presser foot, arranged to tilt universally with reference to said presser foot, said feed part and clamp being on the same side of the presser foot.
30. In a blind stitch sewing machine, the combination of a presser foot, a plunger, means to reciprocate said plunger toward and from said presser foot, and a clamp disposed on the same side of the presser foot as the plunger and mounted to tilt universally relative to the presser foot.
31. In a blind stitch sewing machine, the combination of a presser foot, a plunger, means to reciprocate said plunger toward and from said presser foot, and a clamp disposed on the same side of the presser foot as the plunger and mounted to tilt transversely of the line of feed.
32. In a blind stitch sewing machine, the combination of a presser foot having an opening, a plunger, means to reciprocate said plunger to and from said opening, a feed dog, means to impart 4-way motion to said feed dog, connected to said dog to permit the latter to tilt relative to the presser

foot, a clamp on the same side of the presser foot as said dog and plunger, and a yielding support for said clamp whereon said clamp is mounted to tilt relative to the presser foot.

- 5 33. In a blind stitch sewing machine, the combination of a presser foot having an opening, a plunger, a clamp, means to reciprocate said plunger and clamp toward and from the presser foot, a feed dog, means
10 to move said feed dog in its cyclic operation,

and means to move said feed dog to inoperative position, whereby the goods are subject to manual feed movements subject, however, to the action of the clamp.

In testimony whereof I hereunto set my hand in the presence of two witnesses.

JOHN G. LEWIS.

In the presence of—

GEO. T. MAY, Jr.,

MARY F. ALLEN.
